OTTO MAY, OF NEWARK, NEW JERSEY

FRICITION SPINDLE PRESS AND METHOD FOR THE MAXIMUM UTILIZATION THEREOF

Application filed February 25, 1926, Serial No. 90,502, and in Germany February 27, 1925.

This invention relates to friction spindle presses, and has for its object to provide such a press which has a higher efficiency than the standard press heretofore in use.

5 The object of this invention is to increase the efficiency and therefore output of friction spindle presses.

The invention consists in providing a press and method of operating the same, to increase 10 the efficiency and therefore the output of a friction spindle press by a controlled increase of the centrifugal force energy, to approximate and substantially equal that permissible by the construction of the press.

15 Furthermore, the invention consists in a friction spindle press which by the arrangement of suitable measuring devices and by the arrangement of a controlled centrifugal energy is so improved that the press itself 20 becomes a gauge measuring machine in respect to its maximum output, and thereby the possibility is created to bring about an increase of the output by the controlled increase of the centrifugal energy.

25 In the press of this character heretofore in use, the centrifugal force had to be confined within its maximum, in fear that the press would be destroyed, and so after an approximate safety limit was determined for each

30 press, the velocity and also the rotating mass, that is, the centrifugal energy $(m \frac{v^2}{2})$ was always held within such limitations, so that

35 the user was instructed not to exceed the same, and did not exceed the same for fear of bringing about the destruction of the press. Necessarily, such presses could only be used in respect to part of their output efficiency, and thus a considerable loss in usefulness 40 resulted.

My invention overcomes these defects in that the utilization of the centrifugal force is such as to correspond in respect to its maximum, closely to the maximum resistance to pressure of the press.

It is well known that in the same press by the working of workpieces of different dimensions or materials totally different maximum pressures arise, which are independent

of the workpiece, increasing from zero to the end pressure.

These maximum pressures for an eventual workpiece determine themselves in accordance with the well known energy law applied to friction presses: $E = P \cdot dy$, in which E is energy, P is pressure and dy the deformation distance, or in words:

The energy induced by the flywheel equals the sum of pressures multiplied by deformation movements belonging thereto.

The press itself, that is, the loaded parts, stand naturally under the same eventual pressures as the workpiece and so the frame of the press during a stroke of the plunger 65 will be elastically bent more or less in correspondence with the amount of pressure applied. The deflection of the parts of the frame of the press is therefore directly proportional to the pressure.

Conversely, one can also, on the one hand, out of the momentary deflections of the frame of the press, measure the amount of the momentary pressures. On the other hand, one can, mathematically from energy = Pdy , 75 measure the respective pressures corresponding to the deformation amount dy of the workpiece.

Instruments for the measurement of these two dimensions can be arranged in different 80 ways. In any case, however, the end combination will be such as will be shown by an example hereafter described.

It has been said that the press always stands under the same head as the workpiece, 85 that is, the originally present exactly bounded energy amount which is created by every strike, will be used up in part by the press itself as deformation and friction work; and the energy equation more accurately expressed will read as follows:

$$(2) \quad E = Pdy \text{ (workpiece)} \quad Pdy \text{ (press)}$$

This equation shows that as the workpiece portion of the formula gets smaller, the higher will be the pressure of the press, since E is constant relatively. When the highest possible pressure of the press which is possible is reached, that is when no workpiece is inserted at all, then the press is hard struck 10

and this corresponds to the highest energy element of the press, as none corresponds to the workpiece, which is readily visible from equation 2.

- 5 As a fundamental consideration the press must be so constructed and so dimensioned that it can be "struck hard", that is, that it can, without danger, withstand the highest pressure. In the presses heretofore used, the
 10 manufacturers of such presses would so limit the flywheel velocity or its weight that its revolutions would be limited, because any excess thereof without exact control would soon be so dangerous that the press would be destroyed.
 15

On the other hand, however, it is seen from the foregoing equation 2, that a press of the construction heretofore proposed with its controlled limited energy never can be practically
 20 fully utilized in the sense of technical resistances when with it a workpiece is worked, as the pressure which that press would permit to be utilized is never utilized. But, in accordance with my invention, this highest pressure for any press can be reached when the
 25 centrifugal energy under control is increased.

Assuming that the amount of this permissible increase is known, then it is attained as follows:

- 30 1. The flywheel can be constructively so made, that different weights are provided, whereby the same velocity, but by increased momentum, a larger energy is stored.
 35 2. Or, the velocity is varied under control.

- 35 The operation of the increase is as follows: By means of a measuring apparatus, the "work" (material, pressure, deformation curve) is registered. This curve is then compared with that of the highest possible pressure of the press. If this curve is within the highest possible pressure of press curve, then the work curve can be extended until it cuts the highest pressure curve. The difference between the attained work curve and the point of cutting of said extension and the highest pressure curve, provides the safety element through which the pressure can be increased.
 45

A chart or table will show the said safety curve, and the corresponding position of the operating lever or wheel, which may increase the increase of the centrifugal energy up to its maximum.

As the highest point of the work curve which has been taken may lie so low under the maximum pressure curve that the further progress of the curve cannot be accurately enough foreseen the table is calculated with a corresponding high safety factor in order to prevent a stepping over of the highest pressure for that press. A second taking of a curve by the increased energy will then indicate the consequent delineation of the work curve so accurately that eventually a further addition,—a small dimensioned increment,—to that under the safety factor may be found.

Tests have proven that in all warm pressing, increases up to ten times and more were obtained. This increase indicates not alone, that, for example, the workpiece, which had to be struck five times heretofore, can now be struck only once, but that this strike in consequence of the thereby necessary increase of the accelerated velocity itself, can be carried out quicker than heretofore.
 70

Furthermore, the efficiency output of the press itself is much improved, because it utilizes proportionally a much smaller amount of the now increased acceleration energy of the press as deformation work, as is easily seen from equation 2.
 75

Particularly important appears the improvement when the press is used for warm press work. A friction press is already well adapted for warm pressing in view of its characteristic, that is, at the end of its pressure its increasing deformation velocity theoretically is better adapted for hot pressing than any other kind of press, so that warm pieces during their deformation get much warmer. By the improved press in addition to the mentioned advantages comes also this, that the advantageous velocity action is increased in correspondence to the heat dissipation of the workpiece, so that the deformation can take place quicker than the heat dissipation.
 85
 90

The invention will be more fully described hereinafter. Embodiment thereof will be shown in the accompanying drawings and the inventions themselves will be finally pointed out in the claims.
 95

In the accompanying drawings,

Figure 1, is a printed view of my improved friction spindle presses.

Figure 2, is a printed view of the frame of my improved press showing its means of measuring the distortion of the frame, with the indicating finger at zero position.
 105

Figure 3, is a similar view showing the frame distorted and showing the indicating finger registering the maximum position.
 110

Figure 4, is a similar view of the frame with an indicating or measuring device thereon for determining the amount of deformation of the workpiece from the zero position to its maximum deformation.
 115

Figure 5, is a similar view of the frame of the press having a chart or curve sheet thereon and showing the action of both the distortion indicating finger and the deformation indicating finger so as to mark a curve upon the chart.
 120

Figure 6, shows the maximum pressure curve of the press and also the work curve, with the safety factor indicated thereon.
 125

Similar characters of reference indicate corresponding parts throughout the various views.

Referring to the drawings and more particularly to Figure 1, the operative parts of

the friction press there shown are well known. An example of a friction press is shown in the patent of Debauvais #146,808 of January 27, 1874. In presses of this kind the frame 10 is suitably secured by bolts 11 or the like and has an anvil 12 above which the plunger 13 is suitably guided by guide members 14 and the plunger 13 is secured through a vertical spindle 15 which has keyed at its other end a centrifugal wheel 16. This wheel 16 is operated by contact with vertically arranged friction discs 17 and 18, either one of these wheels being brought in contact with the periphery of the wheel 16. In Figure 1, the periphery of the wheel 16 is in contact with the face of the friction disc 17. As the plunger 13 descends, that is, as the spindle 15 is rotated the wheel 16 from near the center of the friction disc 17 towards its periphery and during this travel from the central portion outwardly the speed of the wheel 16 is increased. It is well known that the greater the radius of the friction disc 17 the greater will be the velocity of rotation given to the wheel 16. It is also well known that the greater the mass or weight of the wheel 16 the greater will be the centrifugal energy and it is well known that this centrifugal energy equals the mass multiplied by the square of the velocity. The friction discs 17 and 18 are suitably keyed to a shaft 19 which is rotated by a suitable motive power. In order to throw either the friction disc 17 or the friction disk 18 into engagement with the wheel 16 a leverage #20 suitably pivoted to the frame of the machine at 21 is provided and this leverage #20 engages a collar 22 and sleeve 24 passing over shaft 19. The free end of the leverage #20 could be provided at 23 with a suitable operating handle placed in a position convenient to the workman. The parts that have been described are not claimed as new.

In order however to give the wheel 16 the greatest velocity of travel under controlled conditions it is advisable to shift the friction wheels 17 and 18 in a vertical direction. For this purpose the side uprights 25 of the frame are provided with suitable trunnions for the shaft 19 and the sleeve 24 and these trunnions are vertically movable by the full maximum. To the side members of the frame 10 a bracket 26 is screwed in which a spindle 27 is arranged and to this spindle 27 and arm 28 is screwed, the end of which passes over a graduated scale 29 of the bracket 26. The spindle 27 is continued in shaft form as at 30 until it reaches the lower part of the trunnion 31 passing for guiding purposes through a bracket 32. A similar upright shaft at the other side of the frame and indicated by 33 is provided which is adapted when raised to move the trunnion 34 with the same degree of movement as the trunnion 31 was moved. For this purpose the shaft 30 is provided with a bevel gear 35

engaging the bevel 36 on a horizontal shaft 37 which at this end has a bevel 38 engaging a bevel 39 screwed on the shaft 33. As the bevel 39 is rotated the screw threaded end of the shaft 33 is moved in the screw threaded bracket 40 and thereby the shaft 33 is raised to the same degree as the shaft 30 was raised by the movement of the spindle 37. The spindle is provided with a suitable handwheel 41 to facilitate its operation. Thus the handwheel 41 may be moved any number of rotations corresponding to the amount of pressure energy desired to be exerted by the press in conformity with the graduated scale 29 on the bracket 26, and in consequence of the rotation of the handwheel 41 the friction discs 17 and 18 will be raised in respect to the wheel 16 to such a degree as conforms to the centrifugal energy desired which in turn corresponds to the amount of energy or pressure of the machine desired.

With every amount of pressure exerted by the plunger 13, a corresponding amount of distortion of the frame 10 of the press is brought about and this can be suitably measured by attaching to the upper side of the frame at 50 a link or lever 51 secured at its lower end to an indicating finger 52 the point of which passes over the scale 53. To this same finger 52 there is pivoted another link or lever 54 having its other end pivoted at 55 to the lower part of the frame 10. When the frame is distorted from its position shown in Figure 2 to its position shown in Figure 3 the indicating finger 52 will be moved over the scale 53 in such a manner as to show the amount of distortion. Thus this arrangement of levers and indicating finger will indicate the amount of distortion of the frame 10. The maximum amount of pressure applied will indicate the maximum amount of distortion possible and any pressure in excess of this would destroy the machine. The amount of pressure which the machine or which a frame of a machine will absorb can be mathematically calculated and becomes a definite criterion for each press depending upon pressures upon the constituency of the materials used in the construction of the press, etc.

It is also necessary, as follows from the formula of energy heretofore outlined to ascertain the amount of deformation of the workpiece. This is done by providing a measuring apparatus which will indicate this deformation and such a device is shown in Figure 4. An elbow lever 60 is provided which is pivoted at 61 to the frame 10 of the machine and the end of the lever 60 passes over a scale 62. The other end of the elbow lever is placed in a position below the plunger 13 so as to contact therewith and an increment movement of the plunger will be translated on the scale 62 by the point of the lever 60. The initial position of the plunger 13 is shown

in full lines in Figure 4 and its position corresponding to final deformation of the work-piece is shown in dotted lines in Figure 4 and this movement of these different positions 5 may be readily read on the scale 62.

The above measuring devices are utilized to form a chart or curve as is well known to engineers. For this purpose there is arranged on the frame 10 on Figures 1 and 5 horizontal 10 guideways 70 in which a board or plate or the like indicated by 71 is arranged and guided by the guideways 70. On this board or plate 71 a paper curve sheet is placed. The very end of the elbow lever 60 is so arranged 15 in respect to this board or plate 71 as to move it in the guideways 70. Then when the frame is distorted the lever 52 is moved and as the curve sheet on the plate 71 is also moved a resulting curve 75 is produced.

20 The curve is more clearly shown in Figure 6 in which the horizontal base line indicates the deformation but dy and a vertical leg or pressure of the press. The curve 75 results from the combined action of the deformation 25 element and the pressure. On these curve sheets there is arranged the maximum pressure curve which is indicated by the horizontal line 76. This curve line is placed upon these curve sheets and can be readily applied 30 by the engineer who constructed the press as it corresponds to the maximum pressure which may safely be used by the particular press. Every press has a different amount of 35 safety pressure and hence with every press that is manufactured and sold there is given out these curve sheets having the maximum pressure indicated thereon conforming with the safety of the press.

When the press is operated with a work-piece 40 with the curve sheet applied as described the indicating members will make the curve 75 on these curve sheets and if that curve takes the outline as shown in Figure 6 it will be seen that an additional surface can 45 be utilized, because as before stated the curve 75 may be continued until it cuts the pressure line 76. The energy surface $o a b$ corresponds to the initial energy in conformity 50 with line 75, and the additional energy surface $o a' b'$, is that additional energy that 55 can be utilized as still within the safety factor and within a pressure equal to or less than that indicated by the pressure line $p-v$ or line 76. If then such a curve as is indicated 60 by 75 is produced by the measuring devices it will indicate to the user of the press that a safety element indicated by the shaded portion 78 or energy surface $a a' b' b$ is still present. And the operator of the press can there- 65 by increase his pressure equal to the maximum pressure indicated by the line 76. It is the additional energy represented by the surface $a a' b' b$, that has heretofore not been 70 utilized in the presses heretofore used and 75 it is one object of my invention to provide

means whereby this additional energy may be 70 safely utilized by the presses. It does not in every case follow that the curve 75 will continue in the same direction. Sometimes these curves will take a more determined vertical 75 upward outline and thus cross or cut the safety pressure curve 76 more rapidly than as shown by the dotted line 77. This feature is determined by the operator with every different character of workpiece preliminarily 80 to the manufacture, use or production use of that press but having once determined the curve for a particular character of workpiece that is to be operated upon, the press is then finally and definitely set, the handwheel 41 is not operated any further and the press is actuated to strike out its output since all of its strikes will be within the safety factor of the press but in closer proximation with the highest maximum pressure allowed by the 85 press.

It will have been seen from the embodiment 90 of the invention that I have described that a friction spindle press which is especially adaptable to certain kinds of press work may be utilized to its utmost maximum pressure utilization, and such a press would have the advantages hereinbefore pointed out.

I have shown in the drawings and particularly in the structure shown in Figure 1, a 95 satisfactory mechanical arrangement to carry out the inventions hereinbefore described but it is clear that changes may be made in the structural elements of the friction spindle press there shown and that also the measuring devices may be modified considerably in their practical and commercial embodiments and still retain the principles of the invention as hereinbefore described. The measuring device that I have shown and described 100 may be substituted by other measuring devices, which are based upon other principles but which however, have the effect of measuring the same dimensions as hereinbefore described.

I therefore do not wish to be limited to the special embodiments shown in the drawings and hereinbefore described in connection therewith as the spirit of my inventions will be fully set forth in the following claims. 110

I claim as new:

1. In combination with a press of the class described, including a deformable frame, an upper platen, a lower platen, and means for forcibly impelling the upper platen to compress a work piece upon the lower platen with accompanying deformation of the frame, indicating means actuated jointly by frame deformation and converging movement of the platens proportional to compression of the work piece whereby indication is given of maximum permissible stress, and maximum press energy may be practically utilized.

2. The combination with a press of the class described, including a frame having 120

members capable of deformation, a lower platen and an upper platen, and means for forcibly impelling one platen toward the other upon a work piece therebetween and 5 against the resistance of the deformable members of the frame, of a movable indicator connected to the deformable members of the frame which are relatively moved in a direction away from each other when the 10 work piece is compressed between the platens and a scale upon which the indicator gives indication of frame deformation.

3. The combination with a press of the class described, including a frame having 15 members capable of deformation, a lower platen and an upper platen, and means for forcibly impelling one platen toward the other, of a movable indicator connected to two parts of the frame which are relatively moved under the stress of the press action, and another indicator arranged to move in 20 accordance with relative movement of the platens.

4. The combination with a press of the 25 class described, including a frame having members capable of deformation, a lower platen and an upper platen, and means for forcibly impelling one platen toward the other, of a movable indicator connected to two parts of the frame which are relatively moved under the stress of the press action, and another indicator arranged to move in 30 accordance with relative movement of the platens, and a chart connected to move with one of the indicators and thus establish with 35 reference to the other indicator a curve of pressure values.

5. A press mechanism of the class described, comprising a frame having uprights 40 and cross members forming substantially a loop, one of the cross members serving as a platen, a relatively movable platen and means for impelling it forcibly toward the platen first named, and a pointer pivotally connected to the frame cross members and giving 45 by its movement indication of frame distortion due to the press pressure.

6. A press mechanism of the class described, comprising a frame having uprights 50 and cross members forming substantially a loop, one of the cross members serving as a platen, a relatively movable platen and means for impelling it forcibly toward the platen first named, a pointer pivotally connected to 55 the frame cross members and giving by its movement indication of frame distortion due to the press pressure, and another pointer pivotied on a frame member and actuated by the movable platen to give an indication of 60 deflection of the work piece.

7. A press mechanism of the class described, comprising a frame having uprights 65 and cross members forming substantially a loop, one of the cross members serving as a platen, a relatively movable platen and means

for impelling it forcibly toward the platen first named, a pointer pivotally connected to the frame cross members and giving by its movement indication of frame distortion due to the press pressure, another pointer 70 pivotied on a frame member and actuated by the movable platen to give an indication of deflection of the work piece, and means for coordinating the indications of the two pointers to establish a curve representing the combined press pressure and work piece deflection. 75

8. A press mechanism of the class described, comprising a frame having uprights, an anvil extending between said uprights and rigid therewith at its ends, a plunger supported in said frame and operable toward said anvil, and means comprising connected relatively movable parts connected between said frame and anvil and operable upon the movement of the plunger to indicate the degree of deformation of a work piece upon 80 said anvil. 85

9. A press mechanism of the class described, comprising a frame having uprights 90 connected by a transverse part, an anvil opposite the transverse part extending between the uprights and rigid therewith at its ends, a plunger mounted in said frame between the transverse part and anvil to compress a work piece against the anvil, and means connected with parts of the frame for indicating the degree of distortion of the frame due to the pressure exerted by the plunger against the work piece and anvil. 95

10. A press mechanism of the class described in claim 9 wherein said means comprises an indicating finger and a pair of links pivotally attached to separate points on the frame at one end and to separate points 105 on the indicating finger at the other. 100

11. A press mechanism of the class described, comprising a frame having uprights, an anvil extending between the uprights and rigid therewith at its ends, a plunger supported by said frame for movement toward the anvil, an indicator comprising a pointer connected to separate parts of the frame to show the distortion of the frame due to the pressure exerted by the plunger, and another indicator comprising a pointer in line with the movement of the plunger to indicate the deformation of a work piece on the anvil. 110

12. A press mechanism of the class described according to claim 11 wherein the indicator of the deformation of the work piece is connected to a device for carrying a curve sheet movably mounted on the frame, in position to co-operate with the pointer of the 125 first-named indicator. 120

In testimony that I claim the foregoing as my invention, I have signed my name hereto.

OTTO MAY.
